6505X

D. SMITH.
CHURN.

Patented Apr. 21. 1831.

(Ap. 21. 1831)

137

6505X

David Smith a citizen of,
Setters Patent.

The Schedule referred to in these Letters Patent
and making part of the same, containing a description
in the words of the said David Smith, himself of his improve-
ment in the Churn.

Be it known that I David Smith, living near Commo-
burgh, Frederick County, Maryland, have made an improve-
ment in the Churn which is described as follows. This Churn consists of the following parts. 1. The frame.
2. The trunk. 3. The Dashers. 4. The bog wheels and Lever.
1. The frame is made of any convenient size by mortising and
tenoning together four logs with the side and end pieces
and to be about 4 feet & 8 inches high. 2. The Trunk
is also made of any convenient size, of a semicircular
figure, made water tight, and has an opening & plug at the
bottom to draw off the milk. It has a projection at the top to
unite with the upper part to be here after described.
3. The Dashers are made in the usual mode but indented
obliquely and turn on an axle in the upper part of the trunk,
which is also made with a semicircular space; and
shut down tight on the lower part by means of three arms
on each side of the Churn, and which are keyed below
the Churn by three bars passing through openings cut
in them. 4. The bog wheels & lever. A bogwheel is fixed
on the axle with the dashers, and a segment wheel
attached to the middle of a lever, works in the bog
wheel which works on the dashers. The top of the
Churn forms a table and has a funnel in it, by which
air or water may be introduced. Operation. The cream
is

is fast into the barrel, the top is keyed down tight, one or two persons work the lever up and down which works the dashers till the butter comes, when it is gathered and taken out, the butter milk is drawn off at the plug. What I claim as my invention, is the construction of the above churn, particularly in the mode of keeping the top to the bottom, the mounted dashers and in the mode of working the dashers, by lever and cog wheels and levers. For a further illustration of my invention I refer to the model and drawings of the same deposited in the Patent Office.

In witness whereof I have hereunto subscribed my Name before two Witnesses and made oath to the same this 15th day of April 1831.
